COMBINED PENCIL AND FLASHLIGHT

Sidney Schwartz, New York, N. Y., assignor to Bantam-Lite, Inc., New York, N. Y., a corporation of New York

Application November 14, 1955, Serial No. 38,879

Term of patent 14 years

(Cl. D74—24)

FIG.1

FIG.4

Fig. 1 is a side elevational view of a combined pencil and flashlight embodying my new design.

Fig. 2 is a top plan view thereof, and

Figs. 3 and 4 are front end and rear end elevational views as seen from lines 3—3 and 4—4 in Fig. 1, respectively.

I claim:

The ornamental design for a combined pencil and flashlight, as shown.
